UNITED STATES PATENT OFFICE.

ALBERTO FINKS, OF NEW BERLIN, NEW YORK.

ROAD-MACHINE.

SPECIFICATION forming part of Letters Patent No. 378,781, dated February 28, 1888.

Application filed May 28, 1887. Serial No. 239,537. (No model.)

To all whom it may concern:

Be it known that I, ALBERTO FINKS, of New Berlin, in the county of Chenango and State of New York, have invented a new and useful 5 Improvement in Road-Machines, of which the following is a specification.

My invention is an improved road-machine, comprising a carriage or main frame, a digger-bar and scraper-bar, and elevating devices 10 therefore.

The invention consists, particularly, in the novel constructions for elevating the said bars and for adjusting the angle of the scraper-bar.

It consists, further, in certain details of construction and novel combinations of parts, as 15 will be hereinafter described and claimed.

In the drawings, Figure 1 is a side elevation of my machine. Fig. 2 is a top plan view thereof, the wheels being removed. Fig. 3 is 20 a view of the front of the machine. Fig. 4 is a detail view of the connection of the upright with the scraper-bar. Fig. 5 is a detail rear view of the scraper and its attachments. Fig. 6 is a plan view of such scraper and some of 25 its attachments. Fig. 7 is a detail view of a part of the digger-bar and one of its teeth. Fig. 8 represents in detail the construction for elevating the bars. Fig. 9 is a detail view of the base-plate of the hand and sprocket-wheel 30 support. Fig. 10 is a detail side view of the scraper-bar and some of its attachments. Figs. 11 and 12 are detail views of the hounds and bolster and their attachments. Fig. 13 is a detail view of the draft-bracket, the clevis, 35 and the connection of the draft-rods therewith. Fig. 14 is a detail view of the hanger devices for elevating the digger and scraper bars. Fig. 15 is a detail view of the bearing attachments for the uprights, and Fig. 16 40 shows, in connection with the central steady-post, the bearing for hand-wheel for adjusting the angle of the scraper.

The main frame has side beams, A A, front beam, B, rear beam, C, diagonal cross-beam D, 45 and short bearing-beam E, arranged between beam D and the rear side, f, of the box F. The front corners of the main frame may be braced at a by angle-plates, as shown in Fig. 2. The frame is also provided, just in rear of 50 the beam D, with a platform, d, on which the operator may stand. The digger G has its bar g re-enforced on its bottom edge by a metallic

plate, g', and the teeth G' have rearwardly-projected lugs g'', which fit in recesses g''' immediately above the said wear-plate g', and the teeth are secured by clips G''. These teeth, it will be seen, are very simple, and may be conveniently forged. The central steady-post, G³, of this digger extends upwardly through a guide, g⁴, on the main frame. 60

The scraper H has its under side and front edge concaved, and I form the said scraper with its body h of iron and its working-edge h' of steel. The end uprights, H', of the scraper and its central steady-post, H'', extend upward 65 through suitable guides, h² h², on the main frame, and the end posts are connected to the scraper by pivoting them between lugs h³, and these lugs may be arranged about midway between the upper and lower edges of the scraper; 70 but I preferably arrange them near to the lower edge of the said scraper, as shown.

The devices for elevating the digger and the scraper are all alike. To the framing are secured the screw supports or frames I, which 75 have openings i for the screws J and guide-rails i' for the nuts K, which are fitted at k to engage the rails, and are moved up and down in the frames by the screws J. The screws have at their upper ends wheels J', by which they 80 may be turned, and such wheels are preferably sprocket-wheels, as shown. From the nuts K depend rods or bars k', which support at their lower ends foot-pieces K', having openings k'' for the passage of the lower end of the 85 screws.

To the foot-pieces K' are pivoted the arms l, formed at the upper ends of links L, which are pivoted at their lower ends to the digger or scraper, as the case may be. By turning 90 any one of the screws the end of the digger or scraper to which it is connected may be elevated or lowered and to any desired degree.

Each of the sprocket-wheels J' is geared by sprocket-belts M with the wheels N. These 95 wheels have sprocket wheels or portions n and hand-wheels n', and are journaled in supports O, having base-plates O', which are slotted at o and secured by bolts o', passed through the slots into the framing, so the said supports 100 may be adjusted from time to time to tighten the belts M. By turning the proper ones of the wheels N the scraper or the digger may be raised at either one or at both ends, as desired.

The draft-brackets P are secured to and depend from the main frame. I form these brackets with front and rear wings, P' P². The front wings, P', have shoulder-like portions p⁵ p', which fit, respectively, under and over the side beams, while the rear wings, P², have shoulder-like portions p², which bear under the side beams, thus bracing the brackets firmly to the beam and relieving the fastening-bolts thereof in large part of the strain. Near their lower ends the brackets have openings q for the clevises Q, on the bolts q' of which are secured the drag-bars R R' for the digger and scraper. The digger drag-bars R connect at their forward ends with the clevises and at their rear ends with the digger-bars, while the scraper-drag connection R' is similarly secured at its forward end, and has its rear end pivotally secured to the scraper. At the points opposite the ends of the digger-bar the connection R' is bent or arched laterally outward at r, for the purpose of permitting a greater degree of endwise movement of the digger-bar, as will be understood from Fig. 2. It is also preferred to form the connection R' in sections, as shown.

In order to adjust the scraper-bar to different angles, to arch the road-bed more or less, I tilt it on its pivotal connection with the end upright, which tilting, by reason of the concave form of the front face and lower edge of the scraper, will serve, as stated, to vary the degree of arch given the roadway. To this end it will be seen that as the scraper is tilted back its front and lower concave edges will combine to form the surface of the roadway, which, by a proper setting of the scraper, may be arched or rounded up to any desired degree within the scope of the scraper shown. This tilting of the scraper may also serve to accommodate it to the difficulty of the work—that is, whether the ground be hard or soft. In the construction shown this tilting of the scraper is effected by means of the construction which I will now describe.

45 Bearing-bars S fit, by means of boxes S' at one end, on and may be adjusted longitudinally along the end uprights of the scraper, being provided with set-screws s, by which they may be clamped in the desired adjustment. These bars extend from boxes S' inwardly, thence rearwardly, and make another bend outward, being provided at their extremities with openings s², forming bearings for the screw-shaft. The boxes S' have portions s³ depending in 50 rear of the uprights, and having openings s⁴ in which the inner ends of screws T are swiveled and secured. The screw T has a pulley, t, fixed to it, and passes through and engages a threaded opening, t', in the connecting-bar T'. This bar has a slot, t², through which the 55 scraper-upright passes, and it extends past said upright and under the bearing-bar S forward, and is connected at its forward end to the upper edge of the scraper. This connection is formed, in the construction shown, by means of a shoulder or lug, T², depending from the connecting-bar in rear of, and a roller, T³,

journaled to said bar and bearing in front of the scraper. This roller is preferred because by it the free oscillation of the scraper is permitted, without any very great friction at the point of contact of the connecting-bar with said scraper.

In order that the scraper may be easily adjusted and that the adjustment may be equal at both ends, I prefer to operate the adjusting-screw by means of a rope, chain, or other belt, U, passed around the pulleys t, and also around an operating drum or shaft, V, having a handle, V', by which it may be turned, and which is journaled on a shaft or stud, w, supported by a frame, W. This frame W has preferably a box or loop-like portion, W', which fits on the central steady-post of the scraper, and may be secured at any point thereon by the set screw w'. By adjusting this support up or down on the steady-post the proper tension of the belt U may be secured.

By the described construction it will be seen that the scraper-blade may be adjusted to any suitable angle, according as it is desired to give the road more or less arch.

In this class of machines it is of great importance to provide some simple strong construction by which the slight degree of turning, which is sometimes desirable in operating the machines, may be permitted. To this end I provide the hounds 1, fixed to the front axle, 2, with short elevated rails 3, on which the rollers 4, journaled to the bolsters 5, turn. This construction is simple, strong, cheap, and will be found very efficient in the practical operation of my machine.

It will be understood that the digger and scraper bars suspended from the main frame may be termed the "operating-bars."

Having thus described my invention, what I claim as new is—

1. In a road-machine, substantially as described, the combination, with the framing and the road-making devices to be elevated, of the screw supported on the main frame and turning in a nut or threaded bearing connected with the road-making devices, a sprocket-wheel on said screw, an operating-wheel, and a belt connecting the sprocket and operating wheels, substantially as set forth.

2. The combination, in a road-machine, substantially as described, of the screw-support having a bearing for the screw and guide-rails, as described, the block or nut engaging said rails and having a threaded opening, the screw journaled in its support and engaging the threaded opening of the nut, the road-making devices, connections for joining said nut or block with the road-making devices, the sprocket-wheel connected with the screw, the operating-wheel, and the belt connecting said wheels, substantially as set forth.

3. The combination of the framing, the screw-supporting frame having a bearing for the screw and guides for the nut-block, the nut or block engaging said guides and having a threaded opening for the screw, the screw

5 journaled in the frame and engaging the threaded opening of the nut, and the hanger-arms pivotally connected at their upper ends to the nut or block and having their lower ends connected with the part to be elevated, substantially as set forth.

4. The nut or block having a threaded opening or bore and provided with depending bars k' , having a foot-piece, K' , perforated at 10 k^2 , the bar l , pivoted at its upper end to the foot-piece K' , and having its lower end connected with the device to be elevated, the guides for said nut or block, and the screw engaging the same, substantially as set forth.

15 5. The combination of the framing, the frame I , secured thereto, and having bearing i and guide-rails i' , the nut or block K , engaging said rails, and having depending arms k' and perforated foot-piece K' , the arm l , pivoted to said foot-piece, the screw journaled in bearing i and engaging the block K , the sprocket-wheel on said screw, the sprocket-wheel n , having hand-wheel n' , and the belt connecting said sprocket-wheels, substantially 20 as set forth.

25 6. In a road-machine, substantially as described, the combination of the digger-bar g , the plate g' , secured to the under side thereof, the bar having a socket, g^2 , above the plate g' , the tooth G' , having lug g^2 , and the clip G^2 , substantially as set forth.

30 7. In combination with the main frame, the digger-bar capable of an endwise oscillation or play, the scraper, and the drag-connections for 35 said scraper extended past the outer ends of the digger-bar and arched laterally outward at points opposite the said digger-bar, substantially as set forth.

35 8. The combination, in a road-machine, with 40 the main frame, the operating bar or bars suspended therefrom, and the drag-connections for connecting such operating-bars with the bracket, of the bracket P , having shoulder-like portions p , p' , and p^2 , substantially as and 45 for the purposes specified.

45 9. The combination, with the scraper pivotally supported, of screws arranged to tilt said scraper on its pivotal supports and provided with pulleys and connections between the said

pulleys, whereby the screws may be turned 50 equally to effect an even adjustment of the scraper, substantially as set forth.

10. The scraper pivotally supported, combined with a bar connected therewith and having a bearing for a screw, a screw engaging 55 said bearing, and a support for said screw, whereby the scraper may be tilted on its pivotal support, substantially as set forth.

11. The combination of the scraper pivotally supported, the bar T' , having shoulder T^2 60 and roller T^3 , engaging on opposite sides of the scraper, the screw engaging said bar, and the support for said screw, substantially as set forth.

12. The combination of the scraper, the upright pivotally connected therewith, the bar connected with the scraper and slotted, whereby it may fit over the upright, the screw engaging said bar, and the support for said screw, substantially as set forth. 65

70 13. The combination of the scraper pivotally supported, the screws arranged to tilt the same on its pivotal supports, and provided with pulleys, the belt connecting said pulleys, the drum or shaft engaged by said belt, whereby 75 the latter may be operated, and an adjustable support for said shaft or drum, substantially as set forth.

14. In a road-machine, the combination of the scraper pivotally supported, the bearing-bar S , secured at one end to the upright and having its opposite end provided with a bearing for the screw, the screw, and the bar engaged by said screw and connected with the 80 scraper, substantially as set forth.

85 15. The combination, in a road-machine, of an operating-bar or road-making device, a screw, a support in which said screw is journaled, a threaded bearing engaged by said screw, guides for said threaded bearing, and a connection joining said threaded bearing with the operating-bar, substantially as and for the 90 purposes specified.
